DESIGN FOR A COMBINED BRUSH AND NOZZLE

Gustaf Einar Lofgren, Riverside, Conn., assignor to Electrolux Corporation, Dover, Del., a corporation of Delaware

Application November 29, 1935, Serial No. 59,820

Term of patent 14 years

To all whom it may concern:

Be it known that I, Gustaf Einar Lofgren, a subject of the King of Sweden, residing at Riverside, in the county of Fairfield and State of Connecticut, have invented a new, original, and ornamental Design for a Combined Brush and Nozzle, of which the following is a specification, reference being had to the accompanying drawing, forming a part thereof.

In the drawing:

Figs. 1 and 2 are perspective views of the brush and nozzle and taken at different angles.

Fig. 3 is a vertical sectional view thereof.

I claim:

The ornamental design for a combined brush and nozzle as shown.

In witness whereof, I have hereunto set my hand and seal at New York, N. Y., this 26th day of November, 1935.

GUSTAF EINAR LOFGREN. [L. S.]
